UNITED STATES PATENT OFFICE.

FREDERICK RAY, OF SHORT HILLS, NEW JERSEY.

RING-TENSIONING APPARATUS.

1,332,573.

Specification of Letters Patent.

Patented Mar. 2, 1920.

Application filed October 16, 1918. Serial No. 258,460.

To all whom it may concern:

Be it known that I, FREDERICK RAY, a citizen of the United States, residing at Short Hills, Essex county, State of New Jersey, have invented certain new and useful Improvements in Ring-Tensioning Apparatus, of which the following is a specification.

The invention relates to an improvement in machines for operating upon divided piston rings for the purpose of setting up stresses therein which are distributed in amount or location so as to cause the rings when in use to exert substantially uniform outward radial spring pressure at all points of their circumferences; and the object is to insure the application of the distributed stresses to the intended portions of each ring, so that the desired uniformity of action under working conditions may be realized.

In machines wherein, for example, the rings are held and moved by a rotatable chuck, and acted upon by variable blow hammer mechanism, in accordance with a definite law, it is very desirable that an exact relation be established between the ring and the distribution of the hammering, as otherwise the resulting system of strains in the ring will be displaced, no portion receiving its proper tensioning. Under such conditions, the two halves of the ring, at opposite sides of the split or gap, will be unsymmetrically affected, as the result of which the ring cannot exert uniform pressure. The present invention prevents this condition occurring and insures a symmetrical distribution of the hammering or stresses with respect to the gap in the ring. This is accomplished by the provision on or in the ring-holder of a lug located at the region of least hammering, where accordingly the gap in the ring should be located in order to insure the proper application and distribution of stresses when the machine is set in operation. Best results are secured by forming the lug as a movable, symmetrically tapered or wedge-form centering member, mounted in a guide of definite location, and adapted to enter the ring gap and by contact with both of the ring ends to register the ring with reference to the mechanism, this centering or registration being wholly independent of the amount of end clearance in the ring, because of the self-adjusting character of the wedge.

In the accompanying drawings illustrating the invention:

Figure 1 is a fragmentary front elevation of a machine embodying the invention;

Fig. 2 is an enlarged vertical transverse section;

Fig. 3 is an enlarged perspective view 60 illustrating the relation of the wedge to a diagonally cut or split ring;

Fig. 4 is a smaller view showing the relation for a lap-joint ring; and

Figs. 5 and 6 are semi-diagrammatic views 65 showing how the centralizing member adapts itself to different widths of gap.

For purposes of illustration the invention has been shown applied to a hammering machine such as is disclosed in the Wasson Patent No. 1,016,380, but it is to be understood that it is not limited thereto or to the use of hammer means bodily movable for producing the tensioning, but may be used with rolling or other machines for introducing radial 75 stresses into piston rings.

While reference is intended to be had to the said Wasson patent for a complete understanding of the illustrative mechanism, it may be briefly stated that the ring *a* is held 80 in a removable ring seat 18, 24, which is in turn held in a chuck body 16 mounted rotatably in a circular opening in a support 13. Means for turning the chuck in a step-by-step manner is represented by a ratchet 25 85 fixed to the chuck body and a feed dog 26 coöperative therewith. The ring seat member 18 is formed with the bottom of the ring seat and with one side shoulder, and the member 24 provides the other side portion, 90 the whole being removably clamped together and against a shoulder 19 on the chuck body, by means of a screw ring 21.

A vertically movable hammer body 38, having a striking portion 32 located over the 95 ring seat, is raised and permitted to fall by a tapered tripping cam (not shown), which is governed by a control cam 46 secured to the rotatable ring chuck and acting upon the hammer mechanism through connections 100 represented by the roller arm 48. In this way the force of the blows is automatically varied upon the different portions of the ring. The shape of the control cam determines the law of the machine, and when the 105 roller 47 of the roller arm rests in the notch 82, the machine is at rest and in readiness to commence hammering at a predetermined point in the ring, that is to say at the gap. In general it may be stated that at this region the hammering should be lightest, that it should increase in a precise manner as the ring moves beneath the pressure agency and until the central point opposite the gap is

reached, and should then decrease in the same manner as the gap again approaches.

In accordance with the present invention the ring seat member 18 is formed at the 5 ring-end region with a recess 50, preferably extending radially through it and closed at its outer end by a screw plug 51. In this recess or chamber a plunger 52 is mounted and guided, its operative end 53 being symmetrically tapered or given a wedge-form, to enter the gap b of the ring. A compression spring 54, confined in the recess between a shoulder 55 on the plunger or centralizing device and the plug 51, serves normally to 10 hold the wedge projected into the ring seat and to permit it to yield as much as may be necessary to accommodate itself to different widths of gap, as indicated in Figs. 5 and 6. Such variations in the gap necessarily result 15 from slight variations in manufacture, and may be corrected at a later stage in the production of the rings.

For the purpose of a removable ring seat, a definite positioning of the centralizing 20 device is secured by the provision of a pin 56 and a socket 57 on the ring seat and chuck body respectively. In addition the cam 46 and the chuck 16 are made relatively adjustable in order that the cam and centering 25 wedge may be set in precisely the proper relation. To this end the cam is secured to the chuck by screws 70 which pass through slotted openings 71 in the cam. The screws when tightened hold the parts rigidly together, but may be loosened in order to permit slight relative turning movement, after 30 which they are again tightened.

The edge of the centralizing wedge should be presented in parallelism with the edges 35 of the slot in the ring and should be kept from turning, for which purpose portions of the coöperative bearing surfaces of the plunger and recess are appropriately formed and the edge disposed in the proper relation thereto. Fig. 3 represents the upper portion 58 of the plunger, beneath the wedge end, as square, and it will be understood that the corresponding part of the recess is 40 similarly formed. For a diagonally cut ring, the edge of the wedge is also arranged diagonally. For a square end ring or for a 45 lap joint ring it should be disposed transversely, and in the latter instance it may be only half the width of the ring seat. As 50 shown in the drawings the edge or tip 59 of the wedge is made of a different and much narrower taper than the remainder of the head. This differential taper accommodates 55 the centralizing device to a much wider range of end clearance variation than would a single taper, and the narrow edge is particularly adapted to enter the gaps of rings having a very narrow clearance. As seen

in Fig. 5, the member may be used with rings 65 having practically no end clearance. All that is necessary is to bring one end of the ring against the member, and then to spring the other end into place, which will force the spring-pressed plunger outward until only 70 its thin edge is between the ends.

What I claim as new is:

1. In ring-tensioning apparatus, the combination with means for imparting stresses to a divided ring which stresses vary symmetrically in the two halves, of a yielding member adapted to enter the ring gap to centralize the same irrespective of the width of end clearance. 75

2. In a machine of the character described, the combination of a ring-holder, means for imparting stresses to a divided ring held therein, said stresses being predeterminedly varied in its different portions, and centralizing means for the ring operative in the 80 gap of the ring. 85

3. A machine of the character described comprising a ring-holder, means for acting upon a ring therein with automatically varying force, said ring-holder having a recess at the ring-end region, and a movable centralizing wedge in said recess. 90

4. In ring-tensioning apparatus, the combination with means for operating upon a divided ring with intensities varied symmetrically in the two halves, of a part having a guide, and a movable centralizing member definitely located by said guide and having a tapered end adapted to enter the 95 gap of the ring. 100

5. A machine of the character described, comprising a ring-holder for holding a ring, means for rotating the same and means for imparting to different portions of the ring varying stresses, said ring-holder having a 105 recess at the ring-end region, a tapered centralizing member guided in said recess, and a spring in the recess acting to project the member. 110

6. In ring-tensioning apparatus comprising means for operating upon a divided ring with intensities varied symmetrically in the two halves, and a centralizing taper lug constructed with a differential taper having a broadly sloping body and a narrowly 115 converging edge. 115

7. In a machine of the character described, the combination of a ring-holder, means for imparting stresses to the ring, a control cam for varying the stresses in the different parts of the ring in accordance with a predetermined law, and a lug on the ring-holder cooperative with the split portion of the ring to centralize it. 120

In testimony whereof, I have signed my name to this specification.

FREDERICK RAY.
